Attorney

UNITED STATES PATENT OFFICE.

RUPERT L. NIXON, OF SOUTH FORT SMITH, ARKANSAS, ASSIGNEE OF ONE-HALF TO.
EMMA F. CASTLE, OF FORT SMITH, ARKANSAS.

NURSING-BOTTLE HOLDER.

1,178,594.

Specification of Letters Patent. Patented Apr. 11, 1916.

Application filed November 27, 1915. Serial No. 63,820.

To all whom it may concern:

Be it known that I, RUPERT L. NIXON, a citizen of the United States, residing at South Fort Smith, in the county of Sebastian and State of Arkansas, have invented certain new and useful Improvements in Nursing-Bottle Holders, of which the following is a specification, reference being had to the accompanying drawings.

10 This invention relates to an improved nursing bottle holder and has for its primary object to provide a device of this character which may be easily and quickly attached to the handle bar of a carriage or to 15 one of the posts of a crib or bed, said device including simple and novel means for easily and quickly clamping the nursing bottle thereon.

It is another and more particular object 20 of the invention to provide a main supporting rod and means for adjustably mounting the same at one end upon the carriage or crib, a relatively adjustable bracket member on the other end of said rod, whereby 25 the same may be swung to various angular positions, and bottle clamping means mounted upon said bracket.

It is a further general object of the invention to provide a device of the above 30 character which is very convenient and serviceable in practical use, may be manufactured at relatively small cost and entirely obviates possible loss of the bottle or breakage thereof.

35 With the above and other objects in view, my invention consists in the novel features of construction, combination and arrangement of parts to be hereinafter more fully described, claimed and illustrated in the accompanying drawing, in which,

Figure 1 is a perspective view showing my improved bottle holder attached to a baby carriage; Fig. 2 is an enlarged side elevation of the holder; Fig. 3 is a section 45 taken on the line 3-3 of Fig. 2; Fig. 4 is a section taken on the line 4-4 of Fig. 2; Fig. 5 is a section taken on the line 5-5 of Fig. 2; Fig. 6 is a section taken on the line 6-6 of Fig. 3; and Fig. 7 is a detail fragmentary elevation of the adjustable bracket.

Referring in detail to the drawing, C indicates a baby carriage or cart of any ordinary or approved type and H the handle bars thereof.

55 The improved bottle holder forming the

subject-matter of the present application includes a main supporting rod 5 which is bent or curved in the form illustrated and is mounted at one of its ends upon a plate 6 for swinging pivotal movement by means 60 of the bolt 7. This plate 6 is provided with spaced openings to receive U-shaped clamping rods 8 which embrace one of the handle bars H of the carriage. One end of each of these clamping bolts or rods is threaded 65 to receive a wing nut, indicated at 9, whereby the plate 6 may be securely clamped in position against longitudinal shifting movement on the handle bar. The plate 6 is provided with a series of spaced openings 10 70 arranged in concentric relation with respect to the pivot bolt 7, and the supporting rod 5 is also provided with an opening 11 adapted to register with any one of the openings 10 in the plate 6. Upon the pivot bolt 7, 75 one end of a leaf spring 12 is engaged, and the other end of this leaf spring has a pin 13 fixed therein which is adapted for engagement through the coinciding openings in the plate 6 and rod 5, whereby the supporting rod is locked against pivotal swinging movement upon said plate.

The nursing bottle, indicated at B, is adapted to be securely clamped in position upon an adjustable bracket. This bracket 85 includes a base plate 14 having an angularly disposed arm 15 centrally formed upon one of its longitudinal edges and provided with a disk-like terminal 16 having an annular series of teeth 17 formed upon one face 90 thereof. The outer end portion of the supporting rod 5 projects downwardly and also terminates in a disk 18 having a corresponding series of teeth 19 formed upon one face for interlocking engagement with the teeth 95 17 on the disk 16. These disks 16 and 18 are centrally bored to receive a clamping bolt 20, upon one end of which a nut 21 is threaded. The other end of the bolt is provided with a head countersunk in the face 100 of the disk 18, as clearly shown in Fig. 3.

The opposite ends of the elongated base plate 14 of the bracket are angularly disposed and upwardly extended as at 22 and 23, respectively, and in these angular ends of the bracket a rod 24 is rotatably mounted. Upon this rod, exteriorly of the nut 22 of the bracket, a ratchet 25 is fixed, and a knurled head 26 secured upon the end of the rod whereby the same may be conven- 110

iently turned. Upon the end 22 of the bracket, a spring-pressed pawl 27 is mounted for engagement with the teeth of the ratchet 25, whereby the rod 24 is held 5 against turning movement in one direction. To the base plate 14, spaced spring steel clamping bands 28 are fixed at one of their ends, the other ends of said spring bands being turned upon themselves and securely 10 fixed to the rotatable rod 24. These spring bands are of sufficient diameter to receive the nursing bottle B and after the bottle has been arranged in the bands beneath the plate 14, the rod 24 is turned in the proper 15 direction to contract the bands upon the wall of the bottle and securely clamp the bottle against the under side of the base plate 14, as clearly shown in Fig. 4 of the drawings, the pawl 27 engaging the ratchet 25 holding 20 said rod against reverse turning movement. Thus, it will be seen that the bottle is securely clamped and held against all possibility of displacement.

The upwardly extending end 23 of the 25 bracket plate 14 is formed with a hook bill 29 which is adapted to be engaged by an eye 30 mounted upon the supporting rod 5. Thus it will be seen that the clamping screw 20 may be loosened and the bracket carrying 30 the nursing bottle swung to the position shown in dotted lines in Fig. 2 of the drawings, and the hook 29 engaged in the eye 20. Thus, the bottle will be supported in a 35 nearly upright position and leakage of its contents prevented.

From the foregoing description, taken in connection with the accompanying drawing, the construction and several advantages of the device will be fully understood. After 40 the bottle has been filled and clamped upon the bracket in the manner above explained, the pin 13 is disengaged from the opening 10 in the base plate 6 and the head 5 swung with respect to the plate 6 so as to properly 45 dispose the bottle, whereby the nipple may be placed in the mouth of the infant. The bottle may be readily disposed at any desired inclination with respect to the supporting rod by adjusting the bracket member 50 upon said rod so that the infant may consume either a portion or all of the contents of the bottle. The bottle, after being once arranged in proper position, is securely held against all possibility of displacement 55 and cannot be thrown from the carriage or bed by the infant and broken, thus avoiding a considerable item of expense.

By the provision of the clamping means for the bottle above described, it will be seen 60 that the band 28 can be contracted to a greater or less extent so that nursing bottles of various diameters can be securely held upon the bracket. The device could obviously also be readily mounted upon various parts of the carriage or bed by adopt-

ing such obvious mechanical changes in the attaching means for the plate 6 as will readily suggest themselves to one skilled in the art. It is also to be understood that the holder is susceptible of various modifications in the form, proportion and arrangement of its several elements and I, therefore, reserve the privilege of adopting all such legitimate changes as may be fairly embodied within the spirit and scope of the 7 invention as claimed.

Having thus fully described my invention, what I desire to claim and secure by Letters Patent is:—

1. In a nursing bottle holder, in combination, an attaching plate, a supporting rod pivotally mounted upon said plate, means for holding the rod in various adjusted positions with respect to said plate, a bracket on the other end of the supporting rod, bottle clamping means mounted upon the bracket including a rotatable rod, and resilient metal clamping bands fixed at one of their ends to the rod and at their other ends to the bracket and adapted to embrace and clamp a bottle upon the bracket when said rod is rotated.

2. In a nursing bottle holder, an attaching plate, a supporting rod and means for adjusting said rod to various angular positions upon the plate, a bracket, means for angularly adjusting the bracket upon the supporting rod and clamping the same in adjusted position, said bracket including an elongated base plate, and manually operable clamping means mounted upon the bracket to clamp the bottle against the under side of said base plate.

3. In a nursing bottle holder, an attaching plate, a supporting rod and means for adjusting said rod to various angular position upon the plate, a bracket, means for angularly adjusting the bracket upon the supporting rod and clamping the same in adjusted position, said bracket including an elongated base plate, a rotatable element mounted upon said bracket, and a resilient clamping band fixed at one of its ends to the rod and at its other end to said bracket adapted to embrace a bottle and clamp the same against the under side of said back plate when said element is rotated.

4. In a bottle holder, a bracket plate, band fixed at one of its ends to said plate and adapted to embrace the bottle and rotatable element mounted upon said plate to which the other end of said band is attached whereby, upon the rotation of said element, the band is wound thereon and a bottle tightly clamped to said plate.

5. In a bottle holder, a bracket plate, resilient contractible band fixed at one of ends to said plate and adapted to embrace bottle, and manually operable means mounted upon said plate to which the other end

the band is connected, whereby the band may be contracted and caused to tightly clamp the bottle to said plate.

6. In a bottle holder, a bracket plate, 5 spaced resilient clamping bands fixed at one of their ends to said plate and adapted to embrace the bottle, and a rotatable rod journaled in the ends of said plate to which the other ends of the clamping bands are fixed 10 whereby, when said rod is rotated, the latter

ends of the bands are wound thereon and said bands contracted to clamp the bottle against one side of the bracket plate.

In testimony whereof I hereunto affix my signature in the presence of two witnesses. 15

RUPERT L. NIXON.
